DESIGN FOR A MERCHANTISE DISPLAY CABINET

Hari C. Timmis, Kendallville, Ind., assignor to McCray Refrigerator Company, Kendallville,
Ind., a corporation of Indiana

Application July 15, 1944, Serial No. 114,411

Term of patent 7 years

(Cl. D80—11)

To all whom it may concern:

Be it known that I, Hari C. Timmis, a citizen of the United States and resident of Kendallville, in the county of Noble and State of Indiana, have invented a new, original, and ornamental Design for a Merchandise Display Cabinet, of which the following is a specification, reference being had to the accompanying drawing, forming a part thereof.

The drawing is a perspective view of a merchandise display cabinet showing my new design.

The dominant feature of the design resides in the portions shown in full lines.

I claim:

The ornamental design for a merchandise display cabinet, substantially as shown and described.

HARI C. TIMMIS.
